UNITED STATES PATENT OFFICE.

GEORGE Y. YASUMURA, OF SEATTLE, WASHINGTON.

ICE-CREAM-CONE MACHINE.

1,295,109.

Specification of Letters Patent. Patented Feb. 25, 1919.

Application filed June 25, 1918. Serial No. 241,893.

To all whom it may concern:

Be it known that I, GEORGE Y. YASUMURA, a subject of the Emperor of Japan, residing at Seattle, in the county of King and State of Washington, have invented a certain new and useful Improvement in Ice-Cream-Cone Machines, of which the following is a specification.

My invention relates to improvements in machines for baking cone shaped pastry receptacles of the form commonly termed ice cream cones and the object of my invention is to provide a machine that is simple in its plan of construction, easy to operate and economical in its consumption of fuel.

Further objects reside in the details of construction hereinafter more fully described and claimed.

20 I accomplish these objects by devices illustrated in the accompanying drawings, wherein—

Figure 1 is a plan view of a machine constructed in accordance with my invention, 25 the arm for supporting the die members in uplifted position being broken away;

Fig. 2 is a view in sectional elevation substantially on broken line 2, 2 of Fig. 1;

Fig. 3 is a plan view of one of the molds 30 as it may appear when in a partly open position; and

Fig. 4, is a view in elevation illustrating the devices for clamping the mold and die sections together.

35 Referring to the drawings throughout which like reference numerals indicate like parts, the numeral 6 designates a base which supports a vertical post formed of three tubular sections 7, 8 and 9.

40 The section 7 is secured to the base 6 by a pipe fitting 10 that also serves as a means of communication between the interior passageway of the post and two pipes 11 and 12 respectively, as shown in Fig. 1, one of 45 which is an air inlet and the other of which is a gas inlet pipe.

The post section 8 is connected with the section 7 by a coupling member 13 and the section 9 is connected with the section 8 50 by a similar coupling member 14.

The post section 8 serves as a pivot on which is mounted a block 15 that rests upon a collar 19 on the top of the coupling member 13 and is provided with five equilateral 55 peripheral faces 16 to each of which are

secured flanges 17 that are formed integral with radially projecting arms 18.

The outer ends of the arms 18 are each provided on each side with four semi-conical shaped recesses 20 that co-act with other parts hereinafter described to form cone-shaped molds.

Pivots secured to opposite sides of the arms 18 adjacent the flange 17 are swinging members 21 that are each provided near 65 their outer ends with mold sections 22 wherein are formed semi-conical-shaped recesses 23 that register with the recesses 20 in the arms 18 to form cone-shaped molds.

The inner ends of the arms 18 are slotted as at 24 for the reception of the ends of the die-plates 25 that are mounted for oscillating movement on pivots 26.

70 The die-plates 25 are provided with a 75 plurality of conical dies 27 that are suitably arranged to fit within the conical molds formed in the sections 20 and 23 in the mold arms 18 and 21, the dies 27 being sufficiently smaller than the molds so that 80 a relatively thin space is left between the walls of the dies and the walls of the molds when the dies are inserted therein, which space may be filled with batter that may be baked to form a cone-shaped pastry 85 receptacle. The outer ends of the members 21 are each provided with outwardly projecting rods or bars 28 upon one of which is pivotally mounted a hook member 29 that may be hooked over the opposite rod 28 as more clearly shown in Fig. 4, to secure the mold sections 22 in engagement with the arm 18.

90 The outer end of the die-plate 25 is also provided with an outwardly directed rod 95 or bar 30 that is adapted to be engaged by a hook 31 which is pivotally mounted on one of the rods 28 and serves to hold the die section securely in contact with the mold sections, the outer end of the rod is 100 bent at right angles to the remaining portion thereof and is adapted to be engaged by a hook 32 on the end of an arm 33 that is pivotally mounted between lugs 34 on a cap 35 on the top end of the post section 9.

105 The arm 33 is provided adjacent the lugs 34 with a leg 36 that is adapted to strike against the top of the cap 35 to hold the arm 33 in an upwardly inclined position. 110

The two rods 28 and the rod 30 are constructed of springy material, so that when they are secured by the hooks 29 and 31 the several mold and die sections will be held securely in contact with each other.

The machine herein disclosed has five radially projecting die and mold sections but it will be understood that either a greater or less number of similar mold sections may be successfully embodied in a practical machine.

The five mold sections are substantially identical in construction so that a description of one section will apply equally well to all of the others.

The coupling member 14 is provided with four radially directed fuel pipes 37, 38, 39 and 40 that are arranged to project outwardly above four of the die and mold members, the fifth fuel pipe being omitted to leave a space where one of the molds may be opened for the purpose of inserting batter and removing the baked cones.

The pipes 37, 38, 39 and 40 are each connected with Y fittings which in turn are each connected with two burner pipes 42 that are perforated as at 43 on their bottom sides so that they will direct jets of gas downwardly on to the top of the die sections.

The coupling member 13 is provided with four radially directed pipes 44 that correspond in relative position to the pipes 37, 38, 39 and 40 and are connected by Y fittings 45 with burner pipes 46 that are perforated in their top sides as at 47 so that they will direct jets of gas upwardly around the mold sections.

If desired an arm 50 may be fixedly secured to one of the upright post sections above the plane of rotation of the molds and may be provided on its outer end with a shelf 51 that may serve as a support for a vessel in which batter for filling the molds may be placed.

The operation of my invention may be described as follows: Gas and air in the correct proportions may be admitted through the pipes 11 and 12 into the passageway within the upright post and permitted to pass outwardly through the coupling members 13 and 14 to the burner pipes 42 and 46 from whence it issues through the perforations 43 and 47 and may be ignited to produce a flame that substantially envelops the die and mold sections.

As soon as the molds have become heated one of the heated molds may be moved into the filling position, the die section may be raised as shown in Fig. 2. The molds and die section are then greased to keep the cooked cones from sticking to said molds and die sections, then a small amount of batter may be placed in each conical recess in the molds, the die section may be lowered to cause the dies 27 to squeeze the batter

into the narrow space between the walls of the dies 27 and the walls of the mold recesses 20 and 23. The molds may then be rotated on the upright post through one fifth of one complete revolution to bring the filled mold between the first set of burner pipes and to bring the next mold into the filling position which next mold may be filled in the same manner as the preceding one. This operation may be repeated until the mold that was first filled has been moved through one complete revolution and allowed to bake the batter therein for a short time between each of the four sets of burner pipes so that when this mold again reaches the filling position the die is raised as shown in Fig. 2. A fin of batter spreads out on top of arm 18 and coalesces with the fin of batter from the other side, whereby the eight cooked cones are joined together. After the die section is raised into the position shown in Fig. 2, the batter, that has run over the sides of the molds when closed, may be removed with a knife, and then the members 21 may be moved outwardly to the positions 90 shown in Fig. 3 leaving the cooked cones resting upon the arm 18 so that the eight cones may be removed as one, by lifting the same, thus facilitating the handling thereof. The cones may be cut apart or otherwise 95 separated at any time thereafter which is found desirable.

As soon as the baked cones have been removed the members 20 and 21 may be moved inwardly into contact with the arm 18 and secured in this position by the hook 29, batter may be inserted, the die section lowered and the mold again moved into the baking position. In this manner a continuous baking process may be maintained. 105

The intensity of the gas flame is regulated so that when an operator works continuously filling the molds and removing the baked cones the cones will have just sufficient time to bake thoroughly in their 110 movement around the post.

When the batter is poured into the mold recesses 20 and 23 and the dies 27 are lowered therein the batter will be crowded out of the recess and a thin film thereof 115 will be caused to cover the top of the arm 18 so that when the baking has been completed the cones will all be connected by a thin section of material and when the arms 21 are moved outwardly away from the 120 arm 18 the baked cones will remain on the arm 18 and may be easily and quickly lifted and disposed of without breaking them apart.

It will be understood that changes in the 125 form of construction and arrangement of parts of my invention may be resorted to within the scope of the following claims.

What I claim is:

1. In a machine of the class described, a 130

- base, a lower tubular post section connected therewith, fuel supply pipes communicating with said lower post section, a medial tubular post section, a coupling connecting said 5 medial tubular post section with said lower post section, radially directed burner pipes carried by said coupling, a block pivotally mounted on said medial post section and provided with a plurality of flat equilateral 10 peripheral faces, a plurality of cone-forming devices secured to the faces of said block and extending radially therefrom at regular intervals, an upper post section, a coupling connecting said medial post section with said 15 upper post section, and a plurality of radially directed burner pipes carried by said last named coupling whereby the path of travel of said cone-forming devices will be between said first named burner pipes and 20 said last named burner pipes.
2. In a machine of the class described, a support, a plurality of molds mounted for simultaneous rotary movement in a horizontal plane around said support, said molds 25 each comprising a rigidly mounted radial arm having recesses in its side edges adjacent the outer end thereof, two other arms pivoted to said radial arm near the inner end thereof for swinging movement toward 30 and away from each side thereof, said other two arms having recesses in their inner side edges adapted to register with the recesses in said radial arm to form molds, bars of slightly resilient material projecting outwardly from the ends of each of said swinging 35 arms, hook members connecting said two bars together to hold said swinging arms in engagement with said radial arm, a die plate pivoted to the inner end portion 40 of said radial arm for swinging movement in a vertical plane, dies on said die plate
- adapted to enter said molds, an angular bar projecting outwardly from the free end of said die plate, and means carried by said support, releasably engageable with said 45 angular bar for holding said die plate in an elevated position with respect to said mold.
3. In a machine of the class described, a supporting post, a block rotatably mounted on said post and provided with a plurality 50 of flat equilateral faces, a plurality of three-part radially projecting molds each having an intermediate arm formed with a flat under end rigidly fastened against one of said flat faces of the block end provided with a 55 longitudinal slot adjacent said inner end, and a die member pivotally connected to each mold within said slot thereof.
4. In a machine of the class described, an upright post, a block rotatably mounted on 60 said post, a plurality of radially projecting molds rigidly carried by said block, vertically swinging dies for said molds, and means to retain said dies in a raised position including an arm provided with a hook and 65 pivotally connected to said post above said molds.
5. In a machine of the class described, an upright post, a block rotatably mounted on 70 said post, a plurality of radially projecting molds rigidly carried by said block, vertically swingable dies for said molds, said dies having angular bars projecting outwardly from the free ends thereof, and means to retain said dies in a raised position including an arm provided with a hook and 75 pivotally connected to said post, said hook being arranged to releasably engage said angular bars of the dies.

In witness whereof, I hereunto subscribe 80 my name this 20th day of June, A. D. 1918.

GEORGE Y. YASUMURA.
